FURNACE GRATE STRUCTURE

John Franklin Masters, Winston-Salem, N. C.

Application April 9, 1943, Serial No. 482,463

3 Claims. (Cl. 126—163)

The invention relates generally to furnaces and primarily seeks to provide a novel grate adaptable for use in furnaces or like structures and in which provision is made for improving combustion of the fuel mass supported on the grate and also for facilitating removal of ashes and clinkers from said mass.

In its more detailed nature the invention seeks to provide a novel grate structure comprising a perforate plate-like body having a circular opening therein through which ash and clinkers can be discharged, and a perforate opening closure element normally mounted over the opening and including a convex surface receivable in said opening and displaceable from the opening to permit discharge of ash and clinkers downwardly through said opening.

Another object of the invention is to provide a grate structure of the character stated in which the closure element comprises a hollow perforate walled spheroid.

Another object of the invention is to provide a grate structure of the character stated in which the perforate plate-like body is dished downwardly toward the circular opening.

With the above and other objects in view that will hereinafter appear, the nature of the invention will be more fully understood by following the detailed description, the appended claims and the several views illustrated in the accompanying drawing.

In the drawing:

Figure 1 is a detail perspective view of the grate per se. Figure 2 is a vertical cross sectional view illustrating a conventional form of furnace with the improved grate structure mounted therein.

Figure 3 is a detail perspective view of the displaceable opening closure spheroid forming a part of the grate structure.

In the example of embodiment of the invention herein illustrated the improved grate structure is illustrated as mounted in a conventional form of furnace wherein is included a wall structure 5 which defines a fire pot above the grate structure and an ash pit below, there being included the usual grate supporting flange 6, fire brick lining 7, a fire door 8, and an ash door 9.

The grate structure per se is formed to include a circular mounting flange 11 adapted to rest upon the flange 6 or other supporting means in the furnace or stove structure in which the grate is mounted, and a concentrically disposed central ring 12 defining a central opening in the grate structure and connected with the mount-

ing flange 11 by radial ribs 13 suitably spaced apart to provide draft air and fine ash passing openings 14 therebetween, one or more sets of intermediate ribs 15 also being provided between the radially disposed ribs in the manner clearly illustrated in Figures 1 and 2. The central opening provided in the ring 12 is designated 16 and provides a passage through which ash and clinkers can be discharged. It will be observed by reference to Figures 1 and 2 of the drawing that the plate-like body comprising the grate structure is dished downwardly toward the central opening 16.

The central grate opening 16 is normally closed by a hollow, perforate walled spheroid generally designated 17. The displaceable spheroid may be composed of a plurality of half ring ribs 18 extending around the spheroid in one direction, and a plurality of intermediate ribs 19 joining the ribs 18 and extending around the spheroid in the opposite direction. The perforate spheroid thus provided is equipped with openings for suitably permitting passage of draft air and fine ash.

When the grate structure including the displaceable spheroid 17 is mounted in the furnace in the manner illustrated in Figure 2 and a fire bed is built above the same, the provision of a very efficient draft is assured and efficient combustion of the fuel can be expected. When it is desired to remove ash or clinkers through the central opening 16 it is an easy matter to displace the spheroid 17 by manipulation of the usual poker structure, and after the discharge of clinkers, or clinkers and ash has been effected the spheroid 17 can be released and will automatically return to its place in the discharge opening 16 of the grate structure as illustrated in Figure 2.

While the grate structure herein illustrated is shown as circular in shape and with the discharge opening 16 centrally disposed therein, it is to be understood that other shapes of grate structures can be provided and the discharge opening 16 need not be placed centrally therein.

I claim:

1. A grate structure for use in furnaces, stoves or the like comprising a fuel bed supporting body having apertures therethrough for the passage of draft air and fine ash and a circular opening therein through which ash and clinkers can be discharged, and a hollow spheroid freely resting in and normally closing said opening, said spheroid having apertures therethrough for the passage of draft air and fine ash and being displace-

able from the opening to permit discharge of ash and clinkers through said opening.

2. A grate structure for use in furnaces, stoves or the like comprising a fuel bed supporting body having apertures therethrough for the passage of draft air and fine ash and a circular opening therein through which ash and clinkers can be discharged, and a hollow spheroid freely resting in and normally closing said opening, said spheroid having apertures therethrough for the passage of draft air and fine ash and being displaceable from the opening to permit discharge of ash and clinkers through said opening, said supporting body being dished downwardly toward the opening therein.

3. A grate structure for use in furnaces, stoves or the like comprising a fuel bed supporting body having apertures therethrough for the passage of draft air and fine ash and a circular opening therein through which ash and clinkers can be discharged, and a hollow spheroid freely resting in and normally closing said opening, said spheroid having apertures therethrough for the passage of draft air and fine ash and being displaceable from the opening to permit discharge of ash and clinkers through said opening, said supporting body being circular in shape and having the opening therein formed in its center and also being dished downwardly toward said opening.

15 JOHN FRANKLIN MASTERS.
